Specification for Design.

Patented Sept. 14, 1920.

Application filed November 14, 1919. Serial No. 338,121. Term of patent 14 years.

To all whom it may concern:

Be it known that I, ARTHUR O. AUSTIN, a citizen of the United States, residing at Barberton, in the county of Summit and State of Ohio, have invented a new, original, and ornamental Design for an Insulator, of which the following is a specification, reference being had to the accompanying drawing, forming a part thereof, and wherein—

Figure 1 is an elevation of an insulator showing my design; and

Fig. 2 is a plan view of the insulator shown in Fig. 1.

I claim:

The ornamental design for an insulator, as shown.

Barberton, Ohio, October 31, 1919.
